UNITED STATES PATENT OFFICE

147,238

DESIGN FOR A COMBINED VELOCIPEDe AND TRAILER

Warner W. Hoople, Dallas, Tex., assignor to
Dallas Engineering Company, Dallas, Tex., a
partnership consisting of Melvin W. Jackson
and Isabel Potts Jackson

Application April 27, 1946, Serial No. 129,039

Term of patent 3½ years

(Cl. D34—15)

To all whom it may concern:

Be it known that I, Warner W. Hoople, a citizen of the United States of America, residing at Dallas, in the county of Dallas and State of Texas, have invented a new, original, and ornamental Design for a Combined Velocipede and Trailer, of which the following is a specification, reference being had to the accompanying drawing, forming a part thereof.

Fig. 1 is a side elevation of a combined velocipede and trailer showing my new design,

Fig. 2 is a plan view of the same, and

Fig. 3 is a front elevation of the combined velocipede and trailer.

I claim:

The ornamental design for a combined velocipede and trailer, as shown.

WARNER W. HOOPLE.
